US0D1063379S

(12) United States Design Patent (10) Patent No.: US D1,063,379 S
(45) Date of Patent: * Feb. 25, 2025

(54) WAIST PACK

(71) Applicant: GUANGZHOU MIGO E-COMMERCE CO., LTD,
Guangdong (CN)

(72) Inventor: Hong Lin, Shantou (CN)

(*) Notice: Patent file contains an affidavit/declaration under 37 CFR 1.130(b).

() Term: 15 Years

(21) Appl. No.: 29/885,556

(22) Filed: Feb. 26, 2023

(51) LOC (15) Cl. 03-01

(57) CLAIM

The ornamental design for a waist pack as shown and described.

DESCRIPTION

FIG. 1 is a front, right and top perspective view of a waist pack showing my new design;

FIG. 2 is a rear, left and bottom perspective view thereof;

FIG. 3 is a front elevational view thereof;

FIG. 4 is a rear elevational view thereof;

FIG. 5 is a left view thereof;

FIG. 6 is a right view thereof;

FIG. 7 is a top plan view thereof; and,

FIG. 8 is a bottom plan view thereof.

The broken lines illustrate portions of the waist pack that form no part of the claimed design.

1 Claim, 8 Drawing Sheets
